UNITED STATES PATENT OFFICE.

WILSON A. ZIMMER, OF CLEVELAND, OHIO, ASSIGNOR, BY MESNE ASSIGNMENTS, TO THE CLEVELAND ICE MACHINE & MANUFACTURING COMPANY, OF LORAIN, OHIO, A CORPORATION OF OHIO.

COMPRESSOR-VALVE.

1,050,048.

Specification of Letters Patent.

Patented Jan. 7, 1913.

Application filed May 16, 1910. Serial No. 561,659.

To all whom it may concern:

Be it known that I, WILSON A. ZIMMER, a citizen of the United States, residing at Cleveland, in the county of Cuyahoga and State of Ohio, have invented a certain new and useful Improvement in Compressor-Valves, of which the following is a full, clear, and exact description, reference being had to the accompanying drawings.

19 This invention relates to compressor valves; that is to say, valves that are employed with the cylinders into which a fluid is introduced and from which it is supplied under compression. Valves of this kind are employed with cylinders into which ammonia is introduced and from which it is supplied under pressure to coils or pipes for the purpose of making ice.

20 The objects of the invention are to provide a valve mechanism for apparatus of this character which is noiseless and in which (particularly in the case of an inlet valve) should the stem break, the valve body will be prevented from dropping into the cylinder and interfering with the operation of the pumping mechanism.

25 With the foregoing objects in view, the invention may be further and generally defined as consisting of the combinations of elements embodied in the claims hereto annexed and illustrated in the drawings forming a part hereof, wherein,—

Figure 1 represents a sectional detail of one side of a compressor cylinder having a 35 valve constructed in accordance with my invention applied thereto; Fig. 2 represents a similar view of the opposite side of said cylinder, similarly equipped; Fig. 3 represents a sectional detail corresponding to the line 40 3—3 of Fig. 4; and Fig. 4 represents a view, partly in section and partly in elevation, illustrating the manner in which the valves are secured to the cylinder.

Describing the parts by reference characters, 1 denotes the head of the cylinder, to one side of which an inlet valve constructed in accordance with my invention is applied. The cylinder head is provided with a lateral port 2 formed in the upper 45 end of the same and communicating with an annular channel 3 formed jointly in a bore extending vertically through the cylinder head and in a bushing 4 fitted into said bore. The vertical bore, to which reference has been made, is substantially cy-

lindrical, but is contracted at its lower end, to form an inclined seat 5 for the complementarily tapered lower end 6 of the bushing 4. This bushing is provided at its upper end with an internal thread adapted to mesh with an external thread 7 formed on a sectional valve carrier and guide. The threaded portion of the bushing 4 is located above a port 8, communicating with the lateral port 2 and with the chamber 9 formed within the lower portion of the bushing. Below this threaded portion and above the port 8, the bushing is provided with a ledge 10 coöperating with the reduced lower end of the valve support or carrier 11 to form a stop for said support or carrier. The lower portion of the bushing 4 is provided with a suitable number of additional ports 8^a communicating with the annular space 3 and insuring a uniform pressure within all parts of the chamber 9. For the purpose of retaining the valve support in position and to insure the registering of the ports 2 and 8, a screw 12 is provided which extends through the upper portion of the bushing and projects into a suitable seat 13 formed in the outer wall of the valve-support 11.

For the purpose of securing the bushing and valve support in place, a locking ring 14 is provided. This ring has an external thread 15 adapted to mesh with a similar internal thread near the upper end of the vertical cylinder bore, which bore is enlarged above the thread, as shown at 16 to provide an annular recess for the reception of the flange 17 projecting from the upper portion of the ring 14. Between the flange 17 and the bottom of the recess, a suitable gasket 18 is inserted, and a similar gasket 19 will be inserted in the portion of the recess above said flange. A tight joint is made at the recess by means of a cap 20, the lower end 21 of which is adapted to be fitted in the annular recess formed between the upper end of the ring 14 and the adjacent portion of the cylinder head, said cap being provided with a pair of flanges 22, having apertures for the reception of bolts 23, the lower ends whereof are threaded into correspondingly threaded apertures in the cylinder head, as shown at 24. The upper end of the ring 14 is provided with radial slots 25 which are adapted to receive inwardly projecting lugs 26 carried by the

lower end of the cap 20, to prevent the unscrewing of the ring 14. Four such slots and two such lugs are shown, the slots being arranged substantially 90 degrees apart and the lugs substantially 180 degrees apart. By adjusting the bolts 23, the cap 21 forms a particularly effective and tight joint with the cylinder head and ring 14.

Reference has been made to the valve support 11. This support is made in complementary sections, two such sections being shown, the sections, when united, being adapted to form a unitary valve-supporting body. This body is provided with a chamber 27 in its upper end, into which chamber projects the valve stem 28, said stem having on its lower end a valve 29 provided with a beveled surface 30 cooperating with the corresponding beveled seat provided outside of and at the lower end of the sleeve 4. The stem is also provided with a projection or shoulder 31, which projection is mounted within the chamber 32 provided in the complementary members of the valve body 11. The upper end of the valve stem is threaded and is provided with a sleeve 33 slideable thereon, said sleeve being provided with an external thread for the reception of an outer sleeve 34. The sleeves 33, 34 form an adjustable piston or follower on the valve stem 28 and the piston is provided at its lower end with a downward extension 35, which forms a double annular seat for the upper ends of the helical springs 36, 37, the lower ends of which are supported by an annular seat formed on a disk 38 mounted on the valve stem. The sleeve 33 and the piston of which it forms a part may be retained in place in any convenient manner, as by means of nuts 39 and a cotter pin 40. By adjusting these nuts, the tension of the springs may be varied. A restricted port 41 communicates with the chamber in the cap 20 surrounding the valve support and with the chamber 27 below the piston on the valve stem 28. In operating the compressors of refrigerating apparatus, it has been found that the jarring or shock received by the valves causes the metal in the valve stems to crystallize, this crystallization resulting in the breaking of the stems. The provision of the restricted port 41, together with the piston formed by the sleeves 33 and 34, causes a dash-pot action to occur in the operation of the valve, whereby the jarring referred to is overcome, the valve is noiseless in operation, and the material of the valve stem is substantially free from crystallization. However, should breakage occur, this breakage always takes place at the upper portion of the valve stem, and the provision of the shoulder 31 in the chamber 32 will prevent the lower portion of the stem from dropping into the cylinder. By making the valve support in parts or sec-

tions the matter of assembling the valve and its support is comparatively easy, the bushing 4 serving to hold the parts of the valve support in operative relation to each other and to support the same in place in the supply bore.

In Fig. 2 there is shown an outlet valve which is shown as employed with the same cylinder as the inlet valve. This valve is similar to the preceding valve in numerous particulars, the main differences between the valves being such as arise from the fact that the valve shown in Fig. 2 is adapted to open by pressure exerted from within the cylinder, while the former valve opens through pressure acting in the opposite direction. In both instances, however, the valve body will be preferably made in parts, the parts being held together and the valve being supported in the cylinder bore by a bushing having its lower end tapered inwardly to fit a tapered seat provided at the inner end of the bore; also, in both instances, the valve stem is provided with a piston operating in a chamber in the valve-supporting body, said chamber communicating by a restricted port with the space surrounding the said chamber, whereby a dash-pot action is secured which renders the valve noiseless and largely prevents the crystallization of the metal of the valve stem. Also, in both instances, springs are placed in the chamber inside of the valve-supporting body, which springs are operatively interposed between the piston on the valve stem and a relatively fixed abutment, means being provided for adjusting the tension of the springs as occasion may require; also, the construction of the clamping or locking ring which holds the bushing and valve-support in place is identical in both cases; so, also, is the construction of the cap and the manner of applying the same to the cylinder and to the locking ring.

Referring now to the form of my invention shown in Fig. 2, 1 denotes the cylinder head, as before, the cylinder head having a bore which is tapered at its inner end, as shown at 42. This bore is provided with an annular channel 43 extending around the same and forming, with the complementary channel in the bushing 44, an annular distributing channel into which the gas admitted to the interior of the bushing 44 may be discharged through suitable ports 45, the bushing being provided with an enlarged port 46 communicating with the outlet port 47 formed in the cylinder head. The lower end of the bushing 44 is tapered inwardly, as shown at 48, to rest upon the seat formed at the inclined lower end of the vertical bore provided in the cylinder head. The bushing is provided with an internal tapered seat 49 for the outlet valve 50, and the upper end of the bushing is provided

with an internal thread 51 which is adapted to be threaded upon the exterior of the valve-supporting body 52, said body being provided with a shoulder 53 which is adapted to bear against the upper end of the bushing. The body 52 is retained in position within the bushing by means of a suitable set screw 54, the inner end of which engages a suitable notch formed in the threaded exterior of said body. The bushing 44 is retained in place by a clamping ring 55 similar to the ring 14 and having an annular flange 56 projecting into a suitable recess 57 provided in the cylinder head, packing 58 being interposed between said flange and the bottom of said recess. The ring 55 will be provided with notches similar to those in ring 14 for the reception of similar inwardly-projecting lugs (not shown) carried by the cap 59, the lower end of said cap fitting in the upper end of the recess 57 and suitable packing 60 being interposed between the bottom of the cap and the flange. It will be understood that the cap 59 is substantially identical with the cap 20 and will be secured in place upon the cylinder head in like manner. The valve 50 is carried by the valve stem 50^a projecting upwardly into the chamber 61 provided at the upper end of the body 52. The valve stem is provided with a shoulder 50^b near the bottom of said chamber but located a distance thereabove and a reduced shank 50^c shown in Fig. 2 as threaded into stem 50^a. This shoulder forms an abutment for lifting the piston 62. Between said piston and an abutment carried by the upper end of the body 52 there are interposed one or more helical springs 63. The valve stem 40 has applied to its upper end an externally-threaded sleeve 64, said sleeve being retained in place upon the valve stem by means of a nut 65. The sleeve 66 is applied to the sleeve 64, being threaded thereon and being provided with an external thread by means of which it may be secured to the upper threaded end of the body 52. The sleeves 64 and 66 form an adjustable abutment for the upper ends of the spring or springs 63. 50 67 denotes a restricted passageway communicating at one end with the space formed in the chamber 61 below the piston 62 and at its opposite end with the chamber surrounding said body.

55 In operation, the movement of the piston in the cylinder and toward the head 1 will unseat the valve 50 against the action of the spring 63, and gas will be discharged through the outlet port 47. The provision of the piston 62 and restricted passageway 67 secures a dash-pot action in the operation of the valve, preventing the quick seating of the valve by the spring or springs 63, thus rendering the valve noiseless and relieving 55 the same from shocks and jars. The move-

ment of the piston away from the head 1 opens the valve 29 against the action of the springs 36, 37 and allows gas to be drawn into the cylinder through the port 2. Uneven movement of the valve is prevented by the dash-pot action secured by the provision of the piston formed by the sleeves 33, 34 and the restricted passageway 41. Similarly, when the piston in the cylinder reaches the end of its stroke or starts back toward the cylinder head, any quick or violent seating of the valve is prevented by this dash-pot action.

The construction described provides a valve mechanism which is very convenient of application to the cylinder head, which may be very readily removed should occasion require; and which reduces to a minimum any chance of leakage of gas to the exterior of the cylinder.

Having thus described my invention, what I claim is:—

1. The combination, with a cylinder provided with a bore having a seat near the inlet end thereof, of a bushing adapted to be applied to said bore and having an end cooperating with said seat, a valve support mounted in said bushing, a valve co-operating with the lower end of the bushing and having a stem in said support, a clamping ring surrounding said support and threaded into the bore beyond said bushing, and a cap carried by said cylinder and inclosing the outer end of the valve support.

2. The combination, with a cylinder having a bore extending through one end thereof and a lateral port communicating with said bore, of a bushing within said bore and adapted to make a tight joint with the interior surface thereof and having a port arranged to communicate with said lateral port and provided above the said port with an inwardly-projecting shoulder, and a threaded portion above said shoulder, a valve supporting body provided with an externally-threaded portion adapted to mesh with the thread above the shoulder on the bushing, and a reciprocating valve having a stem mounted in said body and co-operating with the inner end of the bushing.

3. The combination, with a cylinder having a bore, of a bushing mounted in said bore, a valve-supporting body detachably secured to said bushing, a valve carried by said body, a clamping ring surrounding said body and detachably fitted to the bore outside of the bushing, said ring having an outwardly-projecting flange extending into a recess provided in the cylinder head and surrounding the bore, a cap adapted to inclose the outer end of the valve-supporting body and having its lower end adapted to enter the recess in operative relation to said flange, said ring and said cap having co-operating lugs and recesses for positioning

the same, and bolts securing said cap to the cylinder head.

4. The combination, with a cylinder having a bore, of a bushing mounted in said bore, a valve-supporting body detachably secured to said bushing, a valve carried by said body, a clamping ring surrounding said body and screwed into the bore outside of the bushing, said ring having an outwardly-projecting flange extending into a recess provided in the cylinder head and surrounding the bore, a cap adapted to inclose the outer end of the valve-supporting body and having its lower end adapted to enter the recesses in operative relation to said flange, and bolts securing said cap to the cylinder head.

5. The combination, with a cylinder having a bore and a port communicating with said bore, of a hollow cylindrical bushing adapted to be seated in said bore and make a tight joint with the walls thereof, and having lateral discharge openings and a terminal valve seat, a valve support mounted in said bushing and having a reduced portion projecting past said openings toward said seat, said valve support being made of complementary members adapted to be fitted together and each having a plurality of fractional recesses, and a valve adapted to coöperate with said valve seat and having a stem in said support, said stem having a piston in one of the complete recesses formed by assembling said members and providing a dash pot, and having a projection in the other of the complete recesses so formed.

6. The combination, with a cylinder having a bore and a port communicating with said bore, of a hollow cylindrical bushing adapted to be seated in said bore and make a tight joint with the walls thereof, and having lateral discharge openings and a terminal valve seat, a valve support mounted in said bushing and having a reduced portion projecting past said openings toward said seat, said valve support being made of complementary members adapted to be fitted together and each having a plurality of fractional recesses, one of said recesses being formed in said reduced portion, and a valve adapted to coöperate with said valve seat and having a stem in said support, said stem having a projection in the recess formed in the reduced portion of the support, and also having a piston in the

other of said recesses and forming a dash pot therewith.

7. The combination, with a cylinder having a bore and a port communicating with said bore, of a hollow cylindrical bushing adapted to be seated in said bore and make a tight joint with the walls thereof, said bushing having lateral discharge openings, a terminal valve seat, and an internal ledge on the side of said openings opposite said valve seat, a two part valve support mounted in said bushing and having a shoulder abutting against the said ledge, and having a reduced portion extending past said openings, and a valve adapted to coöperate with said seat and having a stem extending into said support.

8. The combination, with a cylinder having a bore and a port communicating with said bore, part of said bore being threaded, of a hollow cylindrical bushing adapted to be seated in said bore and to make a tight joint with the walls thereof and having lateral discharge openings and a valve seat at one end, a valve support in said bushing and rigidly engaging the walls thereof and extending therebeyond, a valve adapted to coöperate with said seat and having a stem extending into said support, an externally threaded collar screwed into said bore and abutting said bushing and closely surrounding said valve support, and a cap engaging said collar, and inclosing said valve support, said cap being independently secured to said cylinder.

9. The combination, with a cylinder having a bore and a port communicating with said bore, part of said bore being threaded, of a hollow cylindrical bushing internally threaded at its outer end and seated in said bore with its outer end beyond said port and having lateral discharge openings, and a valve seat at its inner end, a valve support screwed into the outer end of said bushing and retained thereby, a valve adapted to coöperate with said seat and having a stem extending into said support, and an externally threaded collar screwed into said bore against the outer end of said bushing and closely surrounding said valve support.

In testimony whereof, I hereunto affix my signature in the presence of two witnesses.
